United States Patent

Des. 242,411
Patented Nov. 23, 1976

242,411

TABLE OR SIMILAR ARTICLE OF FURNITURE

Fred T. Walker, Taylorsville, N.C., assignor to Walker Foundry Company, Inc.

Filed July 3, 1975, Ser. No. 592,822

Term of patent 14 years

Int. Cl. D6—03

U.S. Cl. D6—147

FIG-5FIG-4FIG. 1 is a side elevational perspective view of a table or similar article of furniture showing my new design; FIG. 2 is a top plan view of the table of FIG. 1;

FIG. 3 is a side elevational view of the table of FIG. 1 and taken generally at the arrow 3 of FIG. 2;

FIG. 4 is another side elevational view of the table of FIG. 1 and taken generally at the arrow 4 of FIG. 2;

FIG. 5 is a partial, sectional view, taken generally along the line 5-5 of FIG. 2; and

FIG. 6 is a partial, sectional view, taken generally along the line 6-6 of FIG. 4.

I claim:

The ornamental design for a table or similar article of furniture, substantially as shown.
